UNITED STATES PATENT OFFICE.

ARTHUR W. POPE, JR., OF KENOSHA, WISCONSIN.

PISTON.

Application filed February 21, 1921. Serial No. 446,830.

To all whom it may concern:

Be it known that I, ARTHUR W. POPE, Jr., a citizen of the United States, residing at Kenosha, in the county of Kenosha, State 5 of Wisconsin, having invented certain new and useful Improvements in Pistons, do hereby declare that the following is a full, clear, and exact description of the same.

The invention relates to pistons for internal combustion engines, and consists of 10 the matters hereafter described and particularly pointed out in the appended claims.

In the accompanying drawings Figure 1 is a view showing a central vertical section 15 through a cylinder and a piston embodying the features of my invention; Fig. 2 is a sectional view of the piston on the line 2—2 of Fig. 1 the split piston ring being omitted, and Fig. 3 is a sectional view on the line 20 3—3 of Fig. 1.

Referring to the drawings, 1 designates the water-jacketed cylinder of an internal combustion engine of any suitable construction, while the piston is of the hollow trunk 25 type comprising a head 2 and a skirt 3, the head being provided with the usual circumferential grooves for the split piston rings 4, and the inner surface of the skirt being provided at diametrically opposite points 30 with the usual bosses 5 to receive the crankpin of a connecting rod (not shown), the construction so far described being typical of the conventional automobile engine.

It is a matter of common knowledge that 35 in the operation of internal combustion engines great pressure is created in the cylinder above the piston on the compression stroke of the piston and is enormously increased on its expansion stroke upon exploding the compressed charge, and that consequently gas-tight conditions are necessary 40 between the cylinder and piston. Otherwise the gas or vapor escapes between the piston and cylinder, so that on the compression stroke of the piston there is consequent loss of compression and so diminution of the full power volume of the charge 45 as the latter depends on complete combustion of the charge which in turn depends on perfect compression, and on the explosion 50 stroke there is also loss of power by the fuel escaping past the piston instead of having its expansive force confined above the piston head; also, among further objections, such fuel as leaks by the piston 55 dilutes the engine oil in the crank chamber,

and an excess of lubricating oil produced in the film between the piston and cylinder by excessive clearance causes carbon in the cylinder with its known objections. On the 60 other hand, it is necessary to use pistons of sufficiently reduced diameter to provide clearance for free play between the piston and cylinder to allow for the expansion of the piston caused by the high temperature 65 of the exploding charges and prevent it from binding or sticking both before the cylinder wall becomes heated and after it becomes heated as these parts do not expand equally as their temperatures are not 70 always the same. When the piston and cylinder have substantially the same co-efficient of expansion their tendency to unequally expand is reduced to the minimum, but as the cylinders are usually made of 75 cast-iron the weight of the pistons when made of the same material has proved disadvantageous and objectionable, and on the other hand when it was sought to overcome this latter objection by making the pistons 80 of lighter material, such for example as an aluminum alloy, the comparatively high coefficient of expansion of its material caused the piston when heated to bind on the cylinder under normal clearance or necessitated 85 an excessive amount of clearance between the piston and cylinder with a consequent loss of compression and power, as well as other objections.

In order to materially lighten the weight 90 of the piston and at the same time to compensate for the comparatively higher co-efficient of expansion of a metal providing such decreased weight, I provide a piston composed of a metal lighter and of a higher co- 95 efficient of expansion than the metal of the cylinder and having rings of the same co-efficient of expansion as the cylinder so arranged that the effective diameter of the piston is approximately the same as that of 100 a piston made of the same metal as the rings, and the lighter piston fits the cylinder with the usual clearance but with entire freedom from sticking.

In carrying out my invention, assuming 105 that the cylinders are of cast-iron as in the conventional automobile engine, I make the head and skirt of the piston of metallic material lighter than the cylinder, preferably using any well-known aluminum alloy, for 110 example that commercially known as lynite, and this piston is slotted in several places to

- give it flexibility and is provided with rings having substantially the same coefficient of expansion as the cylinder, one of the rings retarding the expansion of the piston and 5 the other preventing the contraction of its skirt. In practice the piston is slotted longitudinally in several places, in the present embodiment four such slits 6 being shown, and these slits extend through the piston 10 from a point in the head down through the skirt to its lower end. The head is also provided with a series of circumferential slits 7, extending through its wall and preferably located one at the upper end of each of the 15 longitudinal slits 6. These slits give flexibility to the piston; the circumferential slits 7, which in practice are equal in length to about one twelfth the circumference of the head, provide increased flexibility between 20 the head and sections of the skirt to permit the diameter of the head to expand to a greater amount than the diameter of the skirt; and the longitudinal slits 6 allow the divided portions or sections of the skirt to 25 open and close radially.
- A pair of closed rings or bands 8 and 9, of the same coefficient of expansion as the cylinder wall, are arranged on the piston to make its effective diameter approximately 30 the same as that of a piston made of the same metal as the rings themselves. In the usual practice these rings are made of cast iron, corresponding to the metal of the cylinder. The lower ring 8 is sprung into a 35 groove on the inside of the skirt near its bottom as indicated, the sections springing apart to allow the ring to be inserted. This provides primarily for adjustment of the diameter of the skirt by the use of different 40 sized rings, and ring gives rigidity and prevents the piston from contracting or being compressed at the bottom. The upper ring 9 is placed slightly below the upper end of the slits 6 on the outside of the piston as 45 indicated; it is closed or made continuous by brazing, welding or other suitable method. This ring 9 retards the expansion of the piston, and restrains it from expanding beyond the expansion of the ring itself. It 50 furthermore serves as a very desirable bearing surface at the upper end of the piston. As is the usual practice the circumference of the head is reduced to fit loosely in the cylinder, and so all bearing between the cylinder wall and piston occurs on this ring or on 55 the portion of the piston wall which is below this ring. It is apparent therefore that the diameter of the piston at any point below this ring cannot expand a greater amount 60 than the ring itself, and when heat is applied to the piston it will expand approximately the same amount as a piston made of the same metal as the ring. The effective diameter of this piston is approximately the 65 same as the diameter of a piston made en-

tirely of the same metal as the rings, assuming that the two pistons are used and operated under like conditions. A piston constructed as above described obviates the difficulties heretofore attendant upon the use of 70 aluminum pistons in automobile engines due to the comparatively high coefficient of expansion of the aluminum which makes it necessary to allow an excessive amount of clearance between the piston and the cylinder 75 wall, and makes it possible to fit an aluminum piston with the same clearance as used with a cast iron piston in the cylinder of the conventional automobile engine.

A piston made as above described from 80 lynite, an aluminum alloy, with the rings 8 and 9 made of cast iron, the top ring being split, sprung into position and then brazed, and the bottom ring made continuous and snapped into position, was fitted 85 into a conventional cast iron cylinder of an automobile engine with $2\frac{1}{6}$ inch bore, a clearance of 0.0025 of an inch being allowed, and this piston operated satisfactorily at all speeds and both when the engine was 90 cold and after it had run sufficiently long to become thoroughly heated. As the expansion of the piston is restrained by the outer ring, and the internal ring merely provides for adjustment of the diameter of the 95 skirt and prevents contraction of its lower portion it is not necessary in providing for expansion clearance between the piston and cylinder to use an inner ring having a lower co-efficient of expansion than the material of 100 the piston.

Furthermore, by using rings of different radial thickness, or by inserting thin shims or strips of metal between the rings and piston, it is possible to change the effective 105 diameter of the piston to compensate for wear of the cylinder walls after long use.

A piston constructed according to my invention is useful and advantageous in other relations, for example in a high speed compressor or pump.

I claim:

1. In combination with a cylinder of an internal combustion engine, a piston comprising a head and a skirt formed of metal 115 having a higher co-efficient of expansion than the cylinder, a closed ring seated in the outer surface of the head and forming a bearing surface for the upper end of the piston, and a second closed ring seated in 120 the inner surface of the skirt near its bottom, said rings formed of metal of substantially the same co-efficient of expansion as the cylinder.

2. In combination with a cast-iron cylinder of an internal combustion engine, a piston comprising a head and a skirt of aluminum alloy, said head having circumferential slits, and said skirt and head having longitudinal slits, a cast-iron closed ring seated 125

- in the outer surface of the head, and a cast-iron closed ring seated in the inner surface of the skirt near its bottom.
3. A piston for internal combustion engines comprising a head and a skirt of aluminum alloy, said head having circumferential slits and a groove in its outer surface below said slits, said skirt and head having longitudinal slits extending from the 10 circumferential slits through the bottom edge of the skirt, said skirt also having an inner groove near its bottom, a cast-iron ring in said outer groove, and a cast-iron ring in said inner groove.
- 15 4. A piston for engine cylinders comprising a head and a skirt of metal having a higher co-efficient of expansion than the cyl-
- inder, said head having circumferential slots, and said skirt having longitudinal slots, and a closed ring having a lower co-efficient 20 of expansion than the piston seated on its outer surface below the upper ends of the longitudinal slots.
5. A piston for engine cylinders comprising a head and a skirt of aluminum alloy, 25 said head having circumferential slots, and said skirt having longitudinal slots, and a closed ring having a lower co-efficient of expansion than the piston seated on its outer surface below the upper ends of the longitudinal slots to restrain the expansion of the skirt.

ARTHUR W. POPE, JR.
